Primary Examiner — David Muller*Assistant Examiner* — Nathan Johnston(74) *Attorney, Agent, or Firm* — Inventa Capital PLC**CLAIM**

I claim the ornamental design for a dehumidifier, as shown and described.

DESCRIPTION

FIG. 1 is a perspective front view of a dehumidifier of the present invention;

FIG. 2 is a perspective view of the thereof;

FIG. 3 is a front view of the thereof;

FIG. 4 is a back view of the thereof;

FIG. 5 is a top view of the thereof; and,

FIG. 6 is a bottom view of the thereof.
